(57) **CLAIM**

The ornamental design for an outdoor knife as shown and described.

DESCRIPTION

Fig. 1.1 : Perspective

Fig. 1.2 : Right

Fig. 1.3 : Top

Fig. 1.4 : Bottom

Fig. 1.5 : Front

Fig. 1.6 : Back

Fig. 1.7 : Left

The drawings depict the ornamental design for an outdoor knife shown from seven views; fig. 1.1 is a perspective view thereof; fig. 1.2 is a right side view thereof; fig. 1.3 is a top view thereof; fig. 4 is a bottom view thereof; fig. 1.5 is a front view thereof; fig. 1.6 is a rear view thereof; and fig. 1.7 is a left side view thereof.

The broken lines illustrate the boundaries of the claimed design and form no part of the claimed design.

1 Claim, 7 Drawing Sheets
